UNITED STATES PATENT OFFICE.

CHARLES E. WILCOX, OF ANAHEIM, CALIFORNIA.

OIL-WELL PUMP.

Application filed December 27, 1921. Serial No. 524,887.

To all whom it may concern:

Be it known that I, CHARLES E. WILCOX, a citizen of the United States, residing at Anaheim, in the county of Orange and State 5 of California, have invented a new and useful Improvement in Oil-Well Pumps, of which the following is a specification.

My invention relates to oil well pumps. These pumps are ordinarily operated 10 through pump rods, the pump being suspended at the lower end of a long string of tubing which hangs in the well and through which the pump rods pass, being attached at their lower end to a plunger, which is 15 reciprocated by pump rods in a working barrel secured to and forming the lower end of the tubing.

These pumps often operate under extremely adverse conditions due to the presence 20 of fine sand or silt which is carried in the oil. This sand or silt tends to wear out the plunger and working barrel, and it is common practice to provide renewable liners for the pump, which liners are, however, in 25 the standard forms of pumps continuous throughout the length of the pump.

It is an object of my invention to provide an oil well pump which will be so designed that the wear from sand or silt will be a 30 minimum.

It is a further object of my invention to provide a pump which is so constructed that there is little liability of the pump becoming jammed or plugged by sand deposited 35 therein.

It is a still further object of my invention to provide a pump which is provided with liners which are so arranged that they are self adjusting to compensate for irregularities in manufacture, and in which the liners 40 are of such dimensions that they can be readily, accurately, and economically machined.

Further objects and advantages will be 45 made evident hereinafter.

Referring to the drawing, which is for 50 illustrative purposes only,

Fig. 1 is a cross section through the center of a pump embodying my invention.

Fig. 2 is a section on a plane represented 55 by the line 2—2, Fig. 1.

Fig. 3 is a section on a plane represented by the line 3—3, Fig. 1.

Figs. 2 and 3 are on a somewhat larger 60 scale than Fig. 1.

In the form of the invention illustrated in the drawings, the lower end of the tubing is shown at 11. A threaded connection 12 is provided on a plunger 13 for the attachment of the pump rods.

The plunger 13 is of the standard construction consisting of a long cylinder, preferably of soft steel, having its periphery machined to form an accurate cylinder of uniform diameter. Carried in the top of the plunger 13 is a working valve 14 and seated in a collar 15 at the bottom of the pump is a standing valve 16, this valve being provided with a garbutt rod 17 which extends up into the plunger 13, sliding freely therein during the operation of the pump, but being engaged and lifted by the plunger 13 when the same is withdrawn from the pump for purposes of inspection or repair. Parts equivalent to members 12 60 to 17 are at the present time standard in the oil well art.

Secured to the bottom of the tubing 11 is a collar 20, this collar being externally threaded at 21 to fit into one of several barrel sections 22. The barrel sections 22 have shoulders 23 upon each of which a hardened liner 24 rests, the liners each being clamped between one of the shoulders 23 and the end of the next higher barrel section or, in the case of the top barrel section, the collar 21. The liners 24 are somewhat smaller in diameter than the cylindrical cavities 25 formed in the barrel sections 22 in which they are placed. The barrel sections each have a recess 26 formed therein around the plunger 13 below the shoulder 23 and each barrel section terminates in an externally threaded portion 27 which fits into a collar 28 formed on the next lower barrel section. The lowest section 22 is threaded into the collar 15. 70

The liners 24 are preferably formed of hardened steel and are provided with a uniform bore fitting very accurately upon the outside of the plunger 13. These liners 24 80 are free to adjust themselves in a direction parallel to the plane indicated by the line 2—2, thus preventing undue side wear therein in the event that the plunger 13 is not absolutely straight or is slightly out of line. 85

By providing these short liners, sand troubles are reduced to a minimum. This is due to the fact that these liners can be very accurately machined and hardened and as they are self adjusting in the barrel, friction 90

and wear therein are greatly reduced. Moreover, in the event that the well is pumping an oil containing a great deal of sand, this sand is largely excluded from the space between the liner 24 and the plunger 13 due to the accurate fit thereof. In the event that sand gets into the space between the liner 24 and the plunger 13, it is carried out of the space by the subsequent movement 10 of the plunger 13 which is much greater than the length of the liners.

When the pump is first placed in the well, the spaces 26 are filled with hard grease, this hard grease tending to exclude the oil and 15 sand and providing a very perfect lubrication of the plunger.

I do not claim that it is possible to make a pump in which the plunger and liners will not wear in the presence of sand; but by providing a plurality of liners, separated by 20 spaces initially filled with hard grease, I am able, however, to provide for a plurality of wearing surfaces, each of which is independent of the others, and each of which 25 must be progressively broken down before the pump is out of service. In other words, the top liner 24 may become so worn that it will not hold oil without in any way impairing the efficiency of the next lower liner 24, 30 and the next lower liner 24 may, in turn, become impaired without impairing the efficiency of the liners below it. It is thus possible, by providing a plurality of liners, to greatly prolong the life of the pump as compared with those pumps in which the barrel 35 works in a single long cylinder formed of a single liner, or is a plurality of liners placed end to end.

I claim as my invention:

40 1. A working barrel for an oil well pump comprising: a series of liners each adapted to fit on a pump plunger; and means for supporting said liners so as to leave a space around said plunger, and between said liners.

45 2. A working barrel for an oil well pump comprising: a series of liners each adapted to fit on a pump plunger; and means for supporting said liners so as to leave a space 50 around said plunger, between said liners, and so as to allow each of said liners a limited movement in a plane to which the axis of the

plunger is perpendicular to allow for faulty alignment of said plunger.

55 3. A working barrel for an oil well pump comprising: a series of liners each adapted to fit on a pump plunger; and a plurality of barrel sections, each liner being clamped between one barrel section and the next barrel section.

60 4. A working barrel for an oil well pump comprising: a series of liners each adapted to fit on a pump plunger; and a plurality of barrel sections, each section being threaded in an adjacent section, and each liner being clamped between one barrel section and the next barrel section.

65 5. A working barrel for an oil well pump comprising: a series of liners each adapted to fit on a pump plunger; and a plurality of barrel sections, each section being threaded in an adjacent section, and each liner being clamped between externally threaded barrel sections and the next barrel section.

70 6. A working barrel for an oil well pump comprising: a series of liners, each adapted to fit on a pump plunger; and means for supporting said liners so as to leave a space around said plunger and between said liners, said space being filled with a lubricant.

75 7. A working barrel for an oil well pump comprising: a series of liners, each adapted to fit on a pump plunger; and means for supporting said liners so as to leave a space around said plunger between said liners so 80 as to allow each of said liners a limited movement in a plane to which the axis of the plunger is perpendicular to allow for the alignment of said plunger, the spaces between said liner being initially filled with 85 lubricant.

80 8. A working barrel for an oil well pump comprising a series of liners, each adapted to fit on a pump plunger; and a plurality of barrel sections, each liner being clamped between one barrel section and the next barrel section, a space being left around said plunger between said liners, this space being initially filled with lubricant.

90 In testimony whereof, I have hereunto set 100 my hand at Los Angeles, California, this 21st day of December, 1921.

CHARLES E. WILCOX.
